DESIGN FOR A DRESS

Christine Mazola, New York, N. Y.

Application November 7, 1939, Serial No. 88,097

Term of patent 3½ years

To all whom it may concern:

Be it known that I, Christine Mazola, a citizen of the United States and a resident of the city of New York, in the county of New York and State of New York, have invented a new, original, and ornamental Design for a Dress, of which the following is a specification, reference being had to the accompanying drawing, forming a part thereof:

Fig. 1 is a front view of a dress showing my new design.

Fig. 2 is a rear view of the dress shown in Fig. 1.

The characteristic feature of my design resides in the rows of decorative nails applied to the upper portion of the yoke and the bow of the belt and the spotted decorative nails applied to the sleeves and upper portion of the dress in association with the skirt and sleeves as shown.

I claim:

The ornamental design for a dress, substantially as shown and described.

CHRISTINE MAZOLA.
